WASHING TRAY

William C. Singleton, New York, N. Y.

Application April 26, 1945, Serial No. 590,481

2 Claims. (Cl. 4—159)

1

This invention relates to washing trays, and particularly to trays for use in hospitals for washing or shampooing the head of a person while lying down in a horizontal or an inclined position on a bed, operating table, or the like.

An object of the invention is to provide a freely movable tray of the kind referred to, adapted for direct support on a bed, operating table or the like, without requiring any adjustable or separate equipment for supporting the tray, or any abnormal posture of the person on such bed, table or the like.

Another object is to provide a head washing tray adapted for bed use and having the floor of the tray so disposed that the tray completely drains without disturbing the head, and no point on the top surface of the floor is lower than the outlet for the liquid in the tray when the person, whose head is supported on the tray, is lying down in a horizontal or an inclined position.

Another object is to prevent splashing of the washing liquid out either side of the tray near the head or neck and to prevent leakage of the liquid between the neck and the tray wall while the tray provides a clear space for carrying on the washing operations from the rear of the tray back of the head or from either side of the tray.

The foregoing and other objects and features of the invention are attained by the construction and arrangement of the parts of the tray and will be understood more fully from the following detailed description in connection with the accompanying drawings, in which:

Fig. 1 is an elevation in section of a tray, taken on line 1—1 of Fig. 4, and showing the head of a person lying down substantially horizontally on a bed;

Fig. 2 is a section similar to Fig. 1 showing the tray inclined to the horizontal for use with a person in an inclined position;

Fig. 3 is a plan view of the tray of Fig. 1; and Fig. 4 is a front elevation of the tray of Fig. 1.

In the drawings, a tray 10 has a substantially flat floor 11 and side walls 12, 17, 22, 25 upstanding from the edges of the floor. The tray may be constructed of any suitable waterproof and corrosion resistant material, such as stainless steel, enameled steel, hard rubber, or other suitable plastic, the tray being preferably of relatively thin material to provide a light weight construction, the wall 12 being preferably formed integrally with the floor 11. The head 13 of the person lying down on the bed 14 is supported on a rigid, inverted, cup-shaped platform 15, having the cushion 16 of sponge rubber or other suitable

2

resilient material upon the upper surface of the platform, as a rest for the head, the platform 15 being supported directly from the floor 11, and being secured thereto in any convenient manner. It is located near the forward side wall 17 of the tray adjacent the arcuate recessed portion 18 in the forward side wall 17. A cushioning strip 19 of rubber or other suitable resilient waterproof material covers and edge 18 of the recessed portion 19 and folds over each side face of the wall 17. The strip 19 may be vulcanized directly on the wall 17 or may be retained in position by the overlapping construction of the strip, or may be otherwise secured to the wall 17. A bar 20, fast to the under surface of the floor 11, at one side of the head position and parallel with the side walls 12 and 22, serves to elevate the side of the tray adjacent wall 22, while the other side of the tray at wall 12, Fig. 4, acts as a fulcrum supporting the tray. A single drain outlet 23 connects with the tray at the corner between the unelevated side wall 12, the floor 11 and the forward wall 17 for discharging the washing liquid from the tray. The rubber or other suitable flexible drain tube 24, connected with outlet 23, may lead to a pail or sewer connection. The forward wall 17 of the tray is preferably made higher above the floor 11 of the tray, except for the recessed portion 18, than the rear wall 25 of the tray, as shown in Figs. 1 and 4, and forward portions 26 and 27 of the walls 12 and 22, respectively, are similarly preferably at a higher level above the floor 11 than the rear wall 25, in order to prevent splashing of the washing liquid out of the tray.

As will be seen in Fig. 1, the head 13 may rest comfortably upon the cushion 16 on platform 15 while the neck 28 rests upon the cushion strip 19 and seals the space between the wall 17 and the neck 28 to prevent leakage of washing liquid between the neck and the tray. The hair 29 may extend downward to the floor 11, and is kept within the limits of tray by side walls 12, 17, 22 and 25. The washing liquid may be poured on the hair or head by a hose, pitcher or other suitable means, not shown. The forward wall 17 and the higher portions of the tray together with the high portions 26 and 27 of walls 12 and 22, respectively, prevent splashing of the washing liquid from the tray while the nurse or person performing the washing operation is provided with ample space and access to the head 13 and the hair 29, while standing either at the rear of wall 25 or at either side wall 21 or 22.

Since the floor 11 of the tray is substantially flat and the downward pressure of the head 13

tends to sink the forward side 17 of the tray slightly lower than the rear side 25, owing to the yieldable character of the bedding, the liquid within the tray tends to accumulate at the forward wall 17 and at the corner between floor 11 and walls 17 and 12, because of the elevation of one side of the tray by the bar 20 and the depression of forward wall 17 by the head. It will thus be seen that all liquid in the tray is conveniently drained through the outlet 23, without requiring any extra operation. The bar 20 is preferably made of lightweight construction by being formed of sheet material similar to that of the tray, and having a V-shaped cross-section, the upper free ends of the V being made fast by welding or other suitable means to the under surface of the floor 11.

The form of tray described herein has been found particularly effective for hospital and sick bed use because of its light weight construction and the avoidance of any relatively movable parts or separate equipment or adjustment for supporting the tray on the bed, operating table, or the like. Furthermore, the patient or person whose head is being washed may remain in a natural position lying down horizontally as in Fig. 1, or inclined so that washing may be done conveniently with the tray in the position shown in Fig. 2.

I have described what I believe to be the best embodiments of my invention. I do not wish, however, to be confined to the embodiments shown, but what I desire to cover by Letters Patent is set forth in the appended claims.

I claim:

5 1. In a device of the class described, an inclined tray member having a floor portion and supported at one end by a bar of V-shaped cross-section, side walls surrounding the floor portion, an articulate recessed portion in one of the side walls shaped to conform to the contours of the neck of a person whose head is positioned within the tray member, and an inverted cup-shaped platform secured to the floor portion and disposed 10 adjacent to and below the recessed portion and adapted to support the head.

15 2. A device as defined in claim 1 in which the platform is provided with a resilient cushion of sponge-like material upon the upper surface thereof.

WILLIAM C. SINGLETON.
